UNITED STATES PATENT OFFICE

112,186

DESIGN FOR A LIGHTING FIXTURE GLOBE

Albert L. Arenberg, Highland Park, Ill., assignor
to Patent License Corporation, Chicago, Ill., a
corporation of Illinois

Application November 16, 1936, Serial No. 65,937

Term of patent 3½ years

To all whom it may concern:

Be it known that I, Albert L. Arenberg, a citizen of the United States, residing at Highland Park, in the county of Lake and State of Illinois, have invented a new, original, and ornamental Design for a Lighting Fixture Globe, of which the following is a specification; reference being had to the accompanying drawing, forming a part thereof.

In the drawing:

Fig. 1 is a perspective view of the lighting fixture globe, showing my new design;

Fig. 2 is a side view; and

Fig. 3 is a face view.

The circular center portion of the convex face of the globe is of clear glass while the surrounding portion of the convex face is of a character to diffuse light.

I claim:

The ornamental design for a lighting fixture globe, substantially as shown and described.

ALBERT L. ARENBERG.
